UNITED STATES PATENT OFFICE.

JULIEN A. BRIED, OF OAKLAND, CALIFORNIA.

CLOTHES DRIER.

Application filed August 5, 1922. Serial No. 579,929.

To all whom it may concern:

Be it known that I, JULIEN A. BRIED, a citizen of the United States, residing at Oakland, in the county of Alameda and State 5 of California, have invented new and useful Improvements in a Clothes Drier, of which the following is a specification and which is illustrated in the accompanying drawings.

This invention relates to clothes driers for 10 drying the household wash, and has for its particular objects a wash drying device which will project outside of a building, be accessible from an open window, have large capacity for its size, permit of the 15 wash being moved away from the building far enough so that it will not flap against the side of the building and become soiled, and withal a device universal in its application to different size windows, one 20 that is cheap to construct, easy to erect, amply safeguarded against falling, yet easily removed for storing until again wanted.

I attain these and other objects by the 25 device illustrated in the accompanying drawing in which Fig. 1 shows the drier carrying a multiplicity of clotheslines, erected and projecting from the window of a building, the view being shown in perspective.

Fig. 2 shows the device used for fastening the ends of the several clothes drying lines.

Fig. 3 shows a modification of the device shown in Fig. 2.

Fig. 4 shows a modification of the supporting brackets.

By closer reference to the drawings it will be observed in Fig. 1 that the drier consists of an arm 1 carrying an outer bowed 40 cross arm 2, and at the other end a shorter straight arm 3 supported in brackets 4, 4 secured to the lower part of a window frame 5 of a building 6.

The arms are preferably made of pipe 45 as shown, to form a simple strong structure and so the several clotheslines will slide over the arms without the use of pulleys.

The main arm 1 may conveniently consist of two pieces, 1, and 1', of different sizes of 50 pipe telescoping at 7 for varying the length of the device or for taking it apart.

A pin 8 passing through a hole in the larger section 1' and any of the holes 9 in the smaller section serves to hold the 55 inner and outer cross arms in horizontal alignment.

The outer cross arm 2 has a series of wire loops 10 to position a series of separate clotheslines 11, and the inner cross arm 3 has a series of pins 12 for the same purpose. 60

One of the brackets 4 has a slot 13 to pass one of the pins 12 when the main arm 1 is swung almost to a vertical position for inserting or removing the device from the brackets, one end of the cross arm 3 being 65 inserted at a time, all the pins 12 being within the two brackets when the drier is in the operative position shown in the drawing, it being possible to slide it endwise in the brackets only when swung almost vertical 70 with the first pin coincident with the slot 13.

Fig. 4 shows one variation in the form of the supporting brackets, a pair of large screw eyes 4', 4'', with the forward one opened a little to form a slot 13' for the 75 passage of the first pin 12, functioning the same as the plate brackets 4 shown in Fig. 1.

At the top of the window is fastened a hook 14 from which extends a stay wire 15. This stay may be a single wire, cable, 80 or chain, but is here shown as two solid wires 15 and 15' with a short length of chain 16 joining them.

This construction makes it easy to hook the stay over the hook 14 in erecting 85 the device or in removing it, or for the purpose of permitting the drier to drop down against the side of the house when not in use, the outer end of the drier swinging in an arc denoted by the dotted line 22. 90

If the device is allowed to fall against the side of the house as mentioned the upper loop of the stay 15 is simply hung over the head of the pin 8 so that it may be easily reached when again desiring to use the drier. 95

It will be noted that the several clotheslines "fan out," this is done to get plenty of circulation of air between the wash, and the outer cross arm 2 is bowed as shown in order to make all the lines of the same 100 length, so that they are interchangeable and the device more commercial.

The several lines all being the same length simply have a knot tied in each end and both ends are hooked into the special fasteners 17. 105

The fasteners 17 are necessary in order to assemble, or dismantle the drier for storing. The fasteners do not pass through the loops 10 in the outer arm, but this is of no consequence as the loops are large enough to pass the knots on the ends of the ropes for 110

the original insertion of the lines or for their removal.

Fig. 2 shows the fastener drawn in perspective full size with both ends of the rope knotted and inserted in the device, and its operation will be readily understood from the drawing, the knots 18 being simply pushed through the hole 19 and drawn under the slot 20 until the line is seated in 10 the slightly enlarged end of the slot 21.

Fig. 3 shows, also in perspective, a modification of the fastener, being a hollow ball shaped body 17' with separate holes and slots for the insertion of the previously 15 knotted rope ends, all parts functioning as already described being similarly numbered.

It will be readily seen that many modifications may be made in the frame construction, rope locating, rope fastening, bracket 20 design and method of attaching, etc., without departing from the spirit of this invention, and any such apparent modifications are sought to be covered in my appended claims.

25 I claim:

1. In a wash drier, a frame comprising a strut with a transverse arm at one end, and a longer transverse arm at the other end, a series of spaced pins along the shorter 30 arm, and a similar series of spaced eyelets along the longer arm spaced further apart than the pins, the longer arm being bent to make the distance between the successive pins on one arm and the successive eyelets 35 on the other arm substantially equal.

2. A wash drier embracing a frame adapted to be secured to a building and to carry a plurality of wash lines, said frame including a strut adapted to project from 40 the building with a cross arm at the end of the strut, rope spacing devices on the cross arm and a series of clothes lines passing around said cross arm located thereon by said spacing devices.

45 3. In a wash drier, a frame adapted to be secured at one end to a building and extending away from the building, said frame including a transverse member at the end of the frame remote from the building, a 50 series of clothesline loops extending to and around said member and free to travel thereover like a pulley, and spacing means on said member for positioning said loops in spaced relation.

55 4. In a wash drier, a frame having two spaced transverse arms, rope spacing means on said arms, and a series of rope loops passing over and around both arms spaced by said means and being movable over the 60 arms like pulley lines.

65 5. In a wash drier adapted to be secured

to and to project from a building, a frame comprising a transverse arm near the building and a longer transverse arm remote from the building, a series of rope loops passing 65 from the shorter to the longer arm around both arms and divergently spaced away from the building.

6. In a wash drier, a frame comprising a strut with a transverse arm at one end and 70 a longer transverse arm at the other end, the longer arm being curved to form a plurality of similar radii to spaced points along both arms.

7. In a wash drier, a frame comprising a 75 strut with a transverse arm at one end and a longer transverse arm at the other end, the longer arm being curved to form a plurality of similar radii to spaced points along 80 both arms, and means at such points for positioning rope loops extending between said arms.

8. In a wash drier, a line supporting frame embracing two arms and a strut holding them in spaced relation, a plurality 85 of clotheslines passing around both arms, means on said arms for spacing the lines, said lines being each a separate rope joined by means at its ends to form a loop, the loop being movable over the arms like a pulley 90 line and the joining means adapted to form a stop at the arms to limit the travel of the rope over the arms.

9. In a wash drier, a frame embracing a 95 central strut and a transverse arm at each 100 end thereof, a pair of supporting devices adapted for securing said frame to a building and adapted to pivotally support the frame by engaging one of said arms at spaced points, means for sustaining said frame in substantially horizontal extension from the building, and means associated 105 with the supported arm for locking it against removal from the supporting devices while the frame is horizontally extended, and permitting freedom of removal when the frame is not in horizontal extension.

10. In a wash drier, a frame embracing a central strut and a transverse arm at each 110 end thereof, a pair of supporting brackets for securing said frame to a building and adapted to pivotally support said frame by engaging one of said arms at spaced points, the latter arm being insertible and removable from the brackets by endwise movement of the arm only, and means associated with the arm for preventing such endwise movement except at a predetermined point 115 in the pivotal movement of the arm in the brackets.

JULIEN A. BRIED.
